TREATMENT OF HYDROCARBON OILS

Charles C. Towne, Poughkeepsie, N. Y., assignor
to The Texas Company, New York, N. Y., a cor-
poration of Delaware

Application February 6, 1932, Serial No. 591,306

5 Claims. (Cl. 196—52)

This invention relates to the treatment of hydrocarbon oils and has to do particularly with the catalytic treatment in the presence of selenium of petroleum oils to produce a motor fuel 5 of improved anti-knock quality by converting paraffin hydrocarbons into compounds of high anti-knock property.

According to the invention hydrocarbon oils such as petroleum naphthas or gasolines, particularly certain paraffin oils such as straight run 10 gasolines or other straight run petroleum fractions, may be reformed or converted into products of substantially the same boiling range but of improved anti-knock value. The invention may 15 also be useful in the treatment of hydrocarbon oils of somewhat higher boiling point than the desired motor fuel, such as gas oil, wherein the oil may be subjected to high temperatures and high pressures to convert the oil into lower boiling 20 products and simultaneously to transform the lower boiling hydrocarbons into compounds having a high anti-knock value. In the treatment of any oil it is advantageous to employ sufficient pressure to maintain that portion of the oil which 25 is in effective contact with the catalyst in the liquid phase. The nature and scope of the invention will be further understood from the following description of the process and apparatus.

In order that the invention may be more clearly 30 understood reference will be made to the accompanying drawing in which the single figure is a diagrammatic view, partly in section, of one form of apparatus for carrying out the process of the invention.

In the figure, the reference character 2 represents a furnace which is heated by the products of combustion from a burner 4. Positioned within the furnace are tubular heaters 6 and 8; the former located partly in the radiant and partly 40 in the convection section, and the latter situated entirely in the cooler portion of the convection section. Outside of and adjacent to the furnace 2 is another furnace setting 10 which surrounds the lower portion of the series of reaction vessels 12, 14 and 16. A flue 18 connects the furnace 2 with the furnace setting 10 whereby any or all of the products of combustion from the burner 4 may be conducted to the setting 10 or diverted to the stack 26 by suitable regulation 45 of the dampers 22 and 24, respectively. An auxiliary burner 26 is adapted to supply additional heat to the setting 10, if desired. A flue 28 serves to discharge the products of combustion whether from the flue 18 or the burner 26 50 to a stack (not shown).

A pump 30 interposed in fresh feed line 32 charges oil to the inlet of coil 6. Transfer line 34 extends from the outlet of coil 6 to a point near the bottom of the first reaction vessel 12. Vapor 55 lines 36 and 38 extend from the upper portion of

vessels 12 and 14 to the lower portion of the succeeding vessels 14 and 16, respectively. The transfer line 34 and the vapor lines 36 and 38 are adapted to extend below the surfaces of the bodies of the catalyst 40 in the lower portions of the reaction vessels. Pipes 42, 44 and 46 penetrate the bottoms of vessels 12, 14 and 16, respectively, to draw off liquids from the vessels or to charge the catalyst thereto. Lines 48 and 50 serve to transfer liquids from one vessel to another and also to maintain a certain level of liquid oil above the catalyst in the lower portions of the vessels.

A vapor line 52 extends from the top of the reaction vessel 16 to the lower portion of a vaporizer 54. A liquid line 56 connects the vessel 16 with the vaporizer 54 at a point above the point of entrance thereto of the vapors line 52. The lines 52 and 56 are provided with valves 58 and 59, respectively, to control the pressure of the fluids 20 passing therethrough. A pipe 60 extends from the bottom of the vaporizer 54 to withdraw liquids therefrom and to conduct them to the line 62, referred to hereinafter, or to transfer them to a line 64 leading to storage (not shown) by 25 suitable regulation of valves 66 and 68, respectively.

A vapor line 70 connects the upper portion of the vaporizer 54 with a fractionating column or fractionator 72. A vapor pipe 74 extends from 30 the top of the fractionator to a condenser coil 76, which in turn is connected by a condensate line 78 to a receiver 80. The receiver 80 is provided with the usual gas release line 82 and liquid draw-off line 84. A reflux condensate line 86 35 serves to withdraw the condensate collecting in the bottom of the tower 72. A pipe 88 communicating with the line 86 serves to conduct the condensate to storage or other suitable place of disposal, if desired. The line 62 in which is interposed a booster pump 90 is adapted to conduct the reflux condensate withdrawn through line 86 to the heating coil 8 from whence it is transferred through line 92 into transfer line 34, or directly to the lower portion of reaction vessel 45 12. A by-pass line 94 serves to conduct the liquid from line 62 to coil 6 by suitable regulation of valves 96 and 98.

In one method of operation, using an apparatus such as shown in the drawing, an oil such as 50 straight run gasoline or naphtha or other petroleum fraction partially cracked or uncracked of low anti-knock property containing hydrocarbons substantially within the boiling range of commercial gasoline, is charged by pump 30 55 through the feed line 32 into the heating coil 6. In the coil the oil is raised to a conversion temperature and then transferred through line 34 to a point below the surface of the catalyst 40 in the bottom of the first reaction vessel 12. The 60

catalyst is previously charged to the reaction vessels through manholes or in a molten condition through lines 42, 44 and 46, after the apparatus is at operating temperatures. The vapors 5 intimately contact the catalyst in the vessel 12 and then pass through vapor lines 36 and 38 to again contact more catalyst in the vessels 14 and 16. A certain amount of liquids accumulate above the surface of the catalyst in the vessels and the 10 churning effect of the vapors bubbling through the catalyst effects intimate contact between the liquid oil and the catalyst in the bottom of the vessels. The liquid level of the oil in the various vessels is maintained at a substantial depth by 15 the pipes 48 and 50 connecting the various reaction vessels. The pipes 48 and 50 project into the vessels 14 and 16 below the end of the vapor lines 36 and 38, thereby creating a small differential pressure sufficient to cause the vapors to 20 pass through the lines 36 and 38 and to maintain the desired depth of the oil in the bottoms of the vessels.

The reaction vessels may be heated, if desired, to maintain the proper temperature by passing 25 the hot flue gases from the furnace 2 through the flue 18 and around the lower portions of the vessels. In some cases it is desirable to use an auxiliary burner, such as burner 26. The heating of the vessels is often essential in the early 30 stages of the operation in order to keep the catalyst in a molten condition, but after normal operating conditions are attained the heat carried to the vessels by the hot oil flowing continuously thereto through transfer line 34 may 35 be sufficient to maintain a proper temperature, and in the latter instance the flue gases may be diverted to the stack 20. The vessels 12, 14 and 16 are preferably constructed to provide large vapor space for substantial digestion of the 40 vapors passing therethrough. The tops of the reaction vessels are preferably cooler than the bottoms in order to knock back polymers or other high boiling liquids onto the catalyst. The tops of the vessels are normally somewhat cooler than 45 the portion within the furnace setting 10, but nevertheless it is sometimes desirable to have positive cooling in the tops of the vessels and this may be done by well known methods, such as air cooling the exterior of the vessels or by 50 using cooling coils in which an oil, say fresh charge, is preheated; also, it may be advantageous in some instances to provide a reflux tower above the vessels and to permit the condensate or polymers to run back onto the catalyst in the 55 bottom of the vessels.

Vapors and liquid oil are transferred from the last vessel 16 through lines 52 and 56, respectively, to a vaporizer 54. The vaporizer is usually maintained under a substantially reduced pressure by 60 suitable regulation of the control valves 58 and 59 in order to promote vaporization of the lower boiling constituents. Vaporization and thorough stripping of the unvaporized oil is further enhanced by the counterflow of liquids and vapors 65 in the lower baffled portion of the vaporizer. The vapors released in the vaporizer 54 are fractionated in the tower 72 and vapors of the desired end point for a finished distillate are conducted through vapor line 74 to the condenser and the 70 distillate collected in the receiver.

The reflux condensate from fractionator 72 is usually returned as a recycle stock to the heating coils either alone or together with any or all of the liquids withdrawn from the bottom of the 75 vaporizer 54. The character of the liquids deter-

mines whether the recycle stock is heated in coil 6 or coil 8. If the recycle stock has tendencies toward coke depositions in the coils it is advantageous to heat it separately in the coil 8. However, if there is no such advantage it may be combined with the fresh feed and heated in the coil 6.

The catalyst employed in the reaction vessels comprises selenium and under normal operating conditions the catalyst is preferably in a molten condition. While relatively pure metallic selenium is preferable for use according to the invention, nevertheless it is contemplated that an impure form, such as a sludge, or in mixture with other materials to increase the volume or to alter 10 the boiling or melting points. In case it is desired to use the catalyst in a form which may not be in a molten condition at the operating temperatures, then the catalyst may be suspended, loosely packed or arranged on trays or shelves 15 in the reaction vessels in such a manner to provide efficient contact with the oil under treatment.

The catalytic effect of the selenium has been found to be essentially a reaction causing conversion of the paraffins into aromatic compounds. It has been noted in this connection that the percentage of the other constituents of the treated oil, such as unsaturates and naphthenes, remain substantially unchanged during conversion 20 or reforming but there is substantially a conversion of paraffins into aromatics. A particularly significant effect of the catalyst is the decrease in the loss of hydrocarbons as polymers or tars compared with ordinary methods of conversion, and 25 a resulting increase in ultimate yield of the desired motor fuel hydrocarbons. This increase may be due to the prevention by the catalyst 30 of polymerization and the resulting prevention of tar and coke formation, since in treating certain oils the formation of heavier hydrocarbons 35 or polymers is substantially eliminated.

The temperatures employed in the process may vary somewhat, depending on the nature of the oil and on the anti-knock quality desired. In 40 general, temperatures between 400° C. and 600° C. have been found to be satisfactory. In treating the lighter oils a temperature from 460° C. to 480° C. is particularly satisfactory for the production of a motor fuel having an octane number 45 in the region of 80. It will, of course, be understood that higher or lower octane numbers may be obtained by varying the temperatures. When 50 using two coils such as 6 and 8 of the drawing for separately treating the fresh charge and the recycle stock a temperature of 400° C. to 600° C. may be used on fresh feed heating coil 6 and a somewhat lower temperature, say 300° C. to 55 500° C. in the recycle stock heating coil 8.

High pressures have been found to be especially desirable for efficient operation of the process. Pressures may vary between 300-3000 pounds per square inch and highly satisfactory results have been obtained at about 1500 pounds. Higher temperatures and high pressures in the reaction vessels are preferable and in this way the reaction is substantially in the liquid phase. It is not necessary, however, that vaporization of the oil be prevented but it is desirable to maintain the oil which is in effective contact with the catalyst in the liquid phase. The latter is brought about by maintaining sufficiently high pressures to retain the heavier fractions as liquids or to maintain the polymers in the liquid phase 70 75

so that the catalyst may contact the oil in the liquid condition.

While the operation of the invention has been described in connection with the reforming of gasoline or petroleum naphtha of low anti-knock value into a motor fuel of high anti-knock value, it will be understood that an oil of higher boiling range than commercial gasoline, for example, an oil containing the heavy ends of gasoline and light ends of gas oil, or a kerosene, or a gas oil, or a recycle stock, or even a still heavier oil, may be treated to advantage according to the invention. The reduction in yield of polymer and tar formation may be more marked in the case of the treatment of lower boiling oils where reforming can be accomplished with a small yield or substantially no formation of polymers; however, the yield of tar and carbonaceous bodies may be substantially reduced in the treatment of heavier oils as compared with that which normally occurs.

As an example of the results produced by my process, a straight run Pennsylvania gasoline of 40 octane number showing by analysis 3.4% unsaturates, 6.8% aromatics, 12.8% naphthenes and 77% paraffins was treated according to the invention and a motor fuel of 70 octane number and having substantially the same boiling range was produced showing 4.2% unsaturates, 26.0% aromatics, 15.1% naphthenes and 54.7% paraffins. Another sample of the oil reformed to the same octane number under similar conditions of temperature and pressure without the use of selenium as a catalyst produced an oil of 11.2% unsaturates, 15.3% aromatics, 24% naphthenes and 49.5% paraffins, but the volume of polymers and other tarry compounds in the latter operation were increased fourfold over that in which the catalyst was employed.

I am aware that heretofore heavy hydrocarbon oils have been cracked at substantially atmospheric pressure in the vapor phase in the presence of an alloy such as ferrous selenide which presents free selenium to the vapors and therefore no claim to such a process is made in this application.

Obviously many modifications and variations of the invention, as hereinbefore set forth, may be made without departing from the spirit and scope thereof, and therefore only such limitations should be imposed as are indicated in the appended claims.

I claim:

1. The method of increasing the anti-knock quality of motor fuel that comprises maintaining a mass comprising selenium in the lower part of a reaction chamber, applying heat to said mass to maintain it in a molten condition, introducing hydrocarbon oil comprising gasoline constituents into the reaction chamber and subjecting the hydrocarbons in contact with the selenium mass to a temperature within the range of 400°-600° C. under a pressure of upwards of 300 pounds, under conditions in which liquid constituents comprising polymer products of reaction are in contact with the selenium mass, to effect transformation into constituents within the gasoline boiling range of increased anti-knock value, cooling the upper portion of the reaction chamber to effect condensation of constituents comprising polymer products of reaction and directing the resulting condensate into contact with said selenium mass.

2. The method of increasing the anti-knock quality of motor fuel that comprises maintaining a mass comprising selenium in a reaction chamber in a heated condition, introducing hydrocarbon oil comprising gasoline constituents into the reaction chamber, subjecting hydrocarbons in contact with the selenium mass to a temperature within the range of 400°-600° C. under a pressure of upwards of 300 pounds, under conditions in which liquid constituents comprising polymer products of reaction are in contact with the selenium mass, to effect conversion into constituents within the gasoline boiling range of increased anti-knock value, subjecting evolved vapors to dephlegmation to separate out a condensate comprising polymer products of reaction and directing the condensate into contact with the selenium mass.

3. In the manufacture of gasoline of high anti-knock value, the process that comprises maintaining a body of selenium in each of a plurality of reaction chambers, maintaining hydrocarbon oil in each of said reaction chambers, maintaining a temperature therein within the range of 400°-600° C. under sufficient pressure that at least a portion of the hydrocarbon constituents comprising polymer products of reaction is in liquid form, collecting said liquid polymers in the several reaction chambers in contact with the respective bodies of selenium and passing vapors evolved in one reaction chamber to a successive reaction chamber, to thereby effect conversion into gasoline constituents of high anti-knock value.

4. In the manufacture of gasoline of high anti-knock value, the process that comprises maintaining a body of selenium in each of a plurality of reaction chambers, maintaining hydrocarbon oil in each of said reaction chambers, maintaining a temperature therein within the range of 400°-600° C. under sufficient pressure that at least a portion of the hydrocarbon constituents comprising polymer products of reaction is in liquid form, collecting liquid polymers in the several reaction chambers in contact with the respective bodies of selenium, introducing hydrocarbon oil into one of said reaction chambers and passing vapors evolved therein to a successive reaction chamber, to thereby effect conversion into gasoline constituents of high anti-knock value.

5. The method of increasing the anti-knock quality of motor fuels that comprises maintaining a body of selenium in each of a plurality of reaction chambers, maintaining a temperature therein within the range of 400°-600° C. under sufficient pressure that at least a portion of the hydrocarbon constituents comprising polymer products of reaction is in liquid form, heating a hydrocarbon oil comprising gasoline constituents to effect vaporization of said oil, introducing the resulting vapors into the body of selenium in one of said reaction chambers, passing vapors evolved therein to a successive reaction chamber into contact with the body of selenium therein and collecting liquid polymers in the several reaction chambers in contact with the respective bodies of selenium, to thereby effect transformation into constituents within the gasoline boiling range of increased anti-knock value.
